(57) **CLAIM**

The ornamental design for a fuel tank for motorcycle, as shown and described.

DESCRIPTION

FIG. 1 is a rear elevational view of fuel tank for motorcycle showing our new design;

FIG. 2 is a top plan view thereof;

FIG. 3 is a section view taken along line 3—3 in FIG. 2;

FIG. 4 is a section view taken along line 4—4 in FIG. 2;

FIG. 5 is a section view taken along line 5—5 in FIG. 2;

FIG. 6 is a section view taken along line 6—6 in FIG. 2;

FIG. 7 is a section view taken along line 7—7 in FIG. 2; and, FIG. 8 is a reference perspective view of fuel tank for motorcycle showing our new design.

The broken line showing of the environment is for illustrative purposes only and forms no part of the claimed design. The portion encompassed by a solid line is the design sought to be patented.

The design sought to be patented is not visible in the front elevation, left side elevation, and bottom views and accordingly, these views are omitted.
